UNITED STATES PATENT OFFICE.

FREDRICK C. KERST, OF SPRINGFIELD, ILLINOIS; JULIA KERST ADMINISTRATRIX OF SAID FREDRICK C. KERST, DECEASED.

MINER'S SAFETY-CAGE.

SPECIFICATION forming part of Letters Patent No. 740,872, dated October 6, 1903.

Application filed June 16, 1903. Serial No. 161,784. (No model.)

To all whom it may concern:

Be it known that I, FREDRICK C. KERST, a citizen of the United States, residing at Springfield, in the county of Sangamon and State of Illinois, have invented certain new and useful Improvements in Miners' Safety-Cages, of which the following is such a full, clear, and exact description as will enable others skilled in the art to which it appertains to make and use my said invention.

My invention primarily relates to cages such as are employed in hoisting coal and other minerals, but obviously may be applied to elevators of other kinds.

15 The purposes of my invention are to provide a cage having safety devices adapted to prevent the falling of the cage if the hoisting-cable is broken or to prevent too sudden ascent of the cage, said safety devices being so constructed and arranged that immediately on the parting of the cable the dogs of the safety device will engage with the vertical guide-rails by which the movements of the cage are guided and will prevent the descent 20 of the cage; to provide means for holding the clamping-dogs away from the guide-rails during the ordinary operation of the apparatus; to provide effective means for bringing all the dogs simultaneously into engagement with 25 the guide-rails, and to provide a releasing device whereby in case of emergency the dogs may be quickly and effectively operated independently of the parting of the cable.

With these ends in view my invention consists in the novel features of construction and combinations of parts shown in the annexed drawings, to which reference is hereby made, and hereinafter particularly described, and finally recited in the claims.

40 Referring to the drawings, Figure 1 is a perspective view of the complete apparatus. Fig. 2 is an enlarged side elevation of one of the safety devices. Fig. 3 is an enlarged partial side elevation showing the releasing device. Fig. 4 is an enlarged horizontal transverse section through one safety device on the line 4 4 of Fig. 2. Fig. 5 is an oblique transverse section through one set of levers on the line 5 5 of Fig. 2. Fig. 6 is a partial 45 vertical longitudinal section on the line 6 6

of Fig. 2. Fig. 7 is an enlarged top plan of the releasing device detached. Fig. 8 is a vertical longitudinal section on the line 8 8 of Fig. 7. Fig. 9 is an end elevation of the same.

Similar reference - letters designate like 55 parts in the several views.

The main frame of the cage consists of side bars A and A', cross-bars A² and A³, and tie-struts A⁴. The bars A are of flat bar-steel and have their ends swaged to form heads a. 60 The cross-pieces A² and A³ are of channel-bar steel. The ends of the pieces A² are bent and turned back on themselves to form rectangular sockets a², in which the pieces A fit. Keys a' pass through the bars A and hold them 65 firmly in the sockets in the pieces A². The pieces A² abut against the ends of the channel-bars A³. The ends of the struts A⁴ abut against the pieces A² and rods A¹⁰, inclosed in the struts, pass through the pieces A², and 70 bind them firmly against the ends of the struts. The guide-blocks A⁵ and the pieces A' are secured to the pieces A² by bolts a³, which pass through the pieces A' and A² and the blocks A⁵. The lower ends of the lifting-chains A⁶ 75 are connected with clevises a⁴ on the rods A¹⁰. This construction and arrangement of the parts gives great rigidity and strength to the structure. The rod A⁷ slides in the housing A⁸, which is secured on the under side of 80 the pieces A⁸, and the housing projects upward above the framework of the cage, as clearly shown. At the upper end of the rod A⁷ is a clevis a⁵, with which the hoisting-cable is connected. The upper ends of the lifting-chains A⁶ are connected with the rod A⁷ by suitable clevises a⁶. A coiled spring A⁹ surrounds the rod A⁷ within the housing A⁸ and is supported by a washer and nut at the lower end of the rod. Lifting on the rod A⁷ compresses the spring A⁹, and the spring reacts to force the rod quickly downward when the cable parts, thus avoiding the risk of the rod sticking in the housing and failing to fall by gravity.

95 The clamping-jaws and the system of levers operating the same are mounted on plates B, which are suitably secured to the side pieces A' of the cage, as hereinafter fully explained.

Each of the plates B has an arched part b, 100

vertical lugs b' , horizontal bosses b^2 , and vertical channels b^3 . The side pieces A' fit in the channels b^3 of the plates B.

A flat plate B' , transverse to the pieces A' , is connected with the plate B and the pieces A' by bolts b^4 passing through all of the pieces and holding them firmly together. The pieces A' fit tightly in the channels b^3 , prevent transverse movement of the plate B, and give great rigidity to the structure.

Levers B^2 and B^3 are mounted on the lugs b' , respectively.

A spring-support B^4 has its upper end secured to the plates B and B' and has at its lower end a hole (not shown) in which the rod B^5 slides. The upper end of the rod B^5 fits in a fork b^8 in the lever B^2 and is pivotally connected with the lever near its inner end.

A spring B^6 surrounds the rod B^5 , and the lower end of the spring rests on the bottom of the spring-support B^4 , and its upper end abuts against a shoulder b^7 on the rod. When the inner end of the lever B^2 is moved downward, the spring B^6 is compressed. When the pressure is removed from the lever B^2 , the spring reacts to raise the lever.

The lever B^3 has a fork b^9 , in which the forked end of the lever B^2 fits, and has in each side of the fork a slot b^{10} , in which the pin b^{11} , connecting the levers B^2 and B^3 , slides.

Bolts D, having threaded ends d and a central integral collar d' , pass horizontally through the plates B and B' . The collars d' of the bolts D rest against the outer faces of the plates B' . Each of the dogs D' has a web d^2 , pierced by a hole d^3 , in which the reduced part of the bolt D fits and the dog turns freely on the bolt. The lever D^2 fits and turns on the collar d' of the bolt D. The annular wall of the dog D' projects over the hub of the lever and is cut away to form stops d^4 d^5 d^6 , which engage with the edges of the levers to limit the oscillations of the dog. On the outer surface of the dog D' are teeth d^7 , which prevent slipping of the dog when in engagement with the guide-rail. The annular wall of the dog D' surrounds and incloses the end of the lever D^2 and the dog turns around the lever. The lower edge of the lever D^2 striking against the ledge d^6 on the dog turns the dog on the bolt D to cause the teeth of the dog to engage with the guide-rail.

Within the hub of the lever D^2 is a helical spring D^8 , which has one end secured to the hub of the lever D^2 and the other end secured to the dog D', and the spring acts to normally disengage the dog from the guide-rail. When the lever D^2 is turned downward, it compresses the spring and forces the dog against the guide-rail. When the lever is released, the spring reacts to disengage the dog from the guide-rail.

Two bent levers E are mounted to turn on stud-bolts passing through the bosses b^2 of the plates B. The upper ends of the levers E are connected by a rod E' .

The releasing device F is mounted on the

rod E' and is connected with the rod A^7 by a chain E^3 or equivalent connecting device.

The lower member of the lever E has a slot e .

Links D^4 connect the levers B^2 and B^3 with the levers D^2 , respectively. The levers E are connected with the levers B^2 by the same pin e' which connects the levers B^2 with the links D^4 .

When the hoisting-cable pulls on the rod A^7 to lift the cage, the rod as it moves upward pulls on the chain E^3 , thereby moving upward the connecting-rod E' and causing the lower ends of the levers E also to turn upward, thereby moving upward the outer ends of the levers B^2 and B^3 , and through the instrumentality of the links D^4 moving the outer ends of the levers D^2 upward, so as to permit the springs D^8 to turn the dogs and disengage them from the guide-rail. The described movements of the parts cause compression of springs B^6 and A^9 . Upon the parting of the cable the springs B^6 and A^9 react to promptly reverse the described movements and cause the dogs to firmly engage the guide-rails.

In case the rod A^7 should from any cause fail to act promptly upon the parting of the cable or should the engineer lose control of the hoisting machinery while the cage is moving either up or down, I provide means whereby the safety-catches may be quickly and effectively operated by a person on the cage.

The releasing device is mounted midway of the rod E' , and consists of a shell or housing F, a vertical eyebolt F' , pierced by a transverse hole f , a horizontally-slidable locking-bolt F^2 , fitting in the transverse hole in the bolt F' , a spring F^3 , acting to push the locking-bolt through the hole in the eyebolt, a lever F^4 , engaging in the slot in the bolt F^2 , and a lever F^5 , engaging in a fork in the lever F^4 . Small rollers f^1 and f^2 in the slot of the bolt F^2 and the fork of the lever F^4 , respectively, serve to reduce the friction between the parts. The chain E^3 is connected with the eye of the bolt F' . The parts are so constructed and arranged that if the lever F^5 be pulled downward it will retract the bolt F^2 and permit the withdrawal of the pin F' , so as to disconnect the chain E^3 from the rod E' .

If in case of emergency a person on the cage desires to apply the safety device, it is only necessary to pull down on the lever F^5 , thereby releasing the rod E' and permitting the springs A^8 to act to set the dogs in engagement with the guide-rails.

Having fully described my invention, what I claim as new, and desire to secure by Letters Patent, is—

1. In a safety-cage, the combination of a main frame, a vertically-slidable lifting-rod, transverse plates secured to the main frame, collared bolts passing through said plates, levers turning on the collars of said bolts and provided with hubs, dogs surrounding the hubs of said levers and turning on said bolts, springs acting against said dogs, a connect-

ing device connected with said lifting-rod, intermediate levers connecting said first-named levers with said connecting device, and, springs operating said intermediate levers, as set forth.

2. In a safety-cage, the combination of a main frame, transverse plates secured to the main frame, spring-supports secured to said plates, rods slideable in said spring-supports, springs surrounding said rods, levers fulcrumed on said plates and connected with said rods, bolts passing through said plates, dogs mounted on said bolts, levers mounted on said bolts and engaging said dogs, links connecting said last-named levers with said first-named levers, a slideable lifting-rod centrally mounted on said cage and means connecting said lifting-rod with said first-named levers, as set forth.

3. A frame structure for safety-cages, consisting of upright pieces having swaged ends, channel-bar side pieces bent and turned back on themselves to form sockets in which said upright pieces fit, keys passing through said upright pieces, channel-bar cross-pieces abutting against said side pieces, pipes abutting against said side pieces, and bolts passing through said pipes and side pieces and securing said side pieces firmly against the ends of said cross-pieces, as set forth.

4. A frame structure for safety-cages consisting of upright pieces, side pieces to which said upright pieces are secured, cross-pieces abutting against said side pieces, securing devices securing together said side pieces and cross-pieces and a centrally-placed housing secured on the under side of said cross-pieces, as set forth.

5. In a safety-cage, the combination of a

main frame, transverse plates secured on the main frame, curved levers mounted on said plates, a rod connecting said curved levers, a housing centrally mounted on said frame, a lifting-rod slideable in said housing, a spring acting to push said lifting-rod downward, a connecting device connecting said lifting-rod with said connecting-rod, intermediate levers mounted on said plates, springs acting to push said intermediate levers upward, dog-actuating levers mounted on said plates, dogs engaged by said dog-actuating levers, and links connecting said dog-actuating levers with said intermediate levers, as set forth.

6. A safety device for cages consisting of a dog-actuating lever provided with a hub, a dog having an annular wall fitting around the hub of said lever and provided with stops and a spring interposed between said dog and said lever, as set forth.

7. A releasing device consisting of a housing, a bolt detachably connected with said housing and means for releasing said bolt from said housing, in combination with safety devices and a lifting device operatively connected with said releasing device, as set forth.

8. In a safety-cage the combination of a main frame, dogs mounted thereon, a lifting device, dog-operating devices and a releasing device connected with said lifting device and dog-operating devices, as set forth.

In witness whereof I have hereunto subscribed my name at Springfield, Illinois, this 21st day of May, 1903.

FREDRICK C. KERST.
